BELT CONVEYER

Walter Jacob Mann, Plainfield, N. J., assignor to
General Conveyors Limited, Montreal, Canada,
a corporation of Canada

Application February 9, 1933, Serial No. 655,391

28 Claims. (Cl. 198—160)

This invention relates more particularly to improvements in a drag belt conveyer line of the type disclosed in my co-pending application, Serial No. 512,914, filed February 2, 1931. In said 5 conveyer line twin drag belts spaced apart transversely in the same plane and running in the same direction cooperate to drag sheets, such as telegrams, for example, along the line. Each sheet is engaged by both belts, and a medial portion 10 of the sheet bridges the space between the belts. A rib extending along the line and projecting between the belts serves to flex said medial portion of the sheet out of the plane of the belts and thereby hold the sheet against transverse displacement.

An important object of the present invention is to provide satisfactory means for forming a bend in such a conveyer line, involving a twisting of the line.

Other objects of the invention will appear hereinafter.

In the drawings, Fig. 1 is a section on the line 1—1 of Fig. 4, showing in top plan the structure forming the bend in the conveyer line;

Fig. 2 is a side view of a portion of said structure directly at the bend, looking in the direction indicated by the arrow A in Fig. 1;

Fig. 3 is an enlarged section taken approximately on the line 3—3 of Fig. 1, the belt tracks and the supporting structure being omitted to show the training of the belts more clearly;

Fig. 4 is a side view looking in the direction indicated by the arrow B in Fig. 1;

Fig. 5 is a skeletonized perspective view of the 35 belts and pulleys of the line;

Fig. 6 is an enlarged section approximately on the line 6—6 of Fig. 1;

Fig. 7 is a perspective view of a modification 40 of the corner structure wherein the belt tracks extend continuously around the corner, over the peripheries of the corner pulleys; and

Fig. 8 is an enlarged detail section on the line 8—8 of Fig. 7.

The sheet conveyer line includes a pair of conveyer belts 1 and 2 trained to form a pair of companion conveyer reaches 1^a and 2^a arranged side by side along the line in transversely spaced relation and in substantially the same plane. These reaches are driven at the same speed and 45 in the same direction along the conveyer line. Disposed against the conveyer faces of said reaches there is a shield 3 to hold sheets to the belts for drag conveyance. The shield forms a pair of tracks 4 along which the belt reaches travel. A conveyed sheet is disposed across both

tracks 2, as indicated at S in Fig. 6, and engaged by both belts, and a medial portion of the sheet bridges the space between the belts. Between the tracks there is a ridge 5 extending along the line and projecting outward between the belts. 60 This ridge serves to flex said medial portion of the sheet into a loop and thereby hold the sheet against transverse displacement from beneath the belts. Preferably the shield 3 is formed of sheet metal pressed outward to form said ridge. 65 Along its longitudinal edges the shield has beads formed by longitudinally slotted tubing 6 into which the edges of the shield are fitted and secured.

In the present disclosure the conveyer line 70 has an ascending length and a horizontal length continuous with the ascending length. Said horizontal length comprises two continuous reaches disposed at a right angle to each and defining a bend or corner in the line. To form this bend 75 there is provided an arrangement of belt pulleys and of the shield 3 to form a substantially right angular twist in the line. It will be understood that the line may have additional lengths and that the angular relations of the different portions of the line may be varied.

At the lower end of the conveyer line the belts are trained around a pair of coaxially arranged pulleys 7, of the same diameter. The latter are fixed to a shaft 8 driven by a motor 9. At the juncture of the ascending length of the line with the horizontal length the belts are trained over a pair of pulleys 10 coaxially arranged and of the same diameter. At the discharge end of the line the belts are trained under pulleys 11 also coaxially arranged and of the same size. The return reaches of the belts are trained upward from the pulleys 11 over a pair of coaxially arranged pulleys 12, then back along the line around two pulleys 13 at the corner in the line and finally 85 over a pair of coaxially arranged pulleys 14 and downward to the pulleys 7. The axes of said successive pulleys 7, 10, 11, 12 and 14 are in the present instance, all horizontal while the corner pulleys 13 are arranged with their axes vertical 90 to form a quarter twist in the return reach of each belt. Said pulleys 13 are disposed in proper belt receiving relation to the pulleys 12 and in proper belt delivery relation to the pulleys 14.

To train the conveyer reaches 1^a and 2^a around 105 the corner in the line there are pulleys at the corner and pulleys at the opposite sides of the corner cooperating to twist both belt reaches and train their twisted lengths around the corner in proper relation to each other. At the corner

there is a pulley 15 for the belt reach 1^a and a pulley 16 for the belt reach 2^a. Pulley 15 is disposed with its axis vertical and pulley 16 is disposed directly over pulley 15 with its axis canted 5 slightly inward with relation to the corner. Both pulleys are of the same diameter and their peripheries are grooved, as at 17. Between said corner pulleys 15 and 16 and the pulleys 10 there is a set of pulleys to deliver the belts to the 10 corner pulleys and cooperate with the latter to twist the belts. Between the corner pulleys and the pulleys 11 there is another set of pulleys to receive the belts from the corner pulleys and restore the belts to their original plane. The 15 first set includes two coaxially arranged pulleys 18 and 19 disposed directly on the conveyer line. In the present instance said two pulleys are of the same diameter and their common axis is horizontal and parallel to the axis of pulleys 10. 20 Spaced above the conveyer line in a position immediately over the pulley 19 is a pulley 20 with its axis parallel to the axis of the pulleys 18 and 19. Spaced slightly in advance of the pulley 19 is a pulley 21 with its axis horizontal and canted 25 slightly with respect to the axis of pulley 19 to dispose it in proper belt-delivery relation to the corner pulley 16.

The set of pulleys at the opposite side of the corner is similar to the set just described. It 30 includes pulleys 18^a, 19^a, 20^a and 21^a whose arrangement with relation to each other and with relation to pulleys 11 corresponds to the relation of the pulleys of the first set to each other and to the pulleys 10. The pulley 21^a is slightly canted 35 horizontally with respect to the other pulleys of the set to dispose it in belt-receiving relation to the corner pulley 16.

The belt reach 1^a is trained from one of the pulleys 10, forward beneath the pulley 18, around 40 the corner pulley 15 and forward beneath the pulley 18^a to one of the pulleys 11. The corner pulley 15 and the pulleys 18 and 18^a cooperate to twist said belt reach a quarter turn. The companion belt reach 2^a is trained from the other 45 pulley 10 forward beneath the pulley 19, upward over the pulley 20 and downward under the canted pulley 21, thereby forming a loop in the belt reach permitting it to be twisted slightly for delivery to the canted corner pulley 16. From 50 pulley 16 said belt reach is trained forward beneath pulley 21^a, upward over pulley 20^a and downward under pulley 19^a to form another loop in the belt enabling it to be twisted back to its original plane. The pulleys 10, 18 and 19 cooperate to train the companion belt reaches forward in a horizontal plane and parallel to each other. The belt twisting pulleys twist the reaches to dispose them substantially at a right angle to said plane and maintain them in proper co-operating relation. Between the pulleys 18^a and 55 19^a and the pulleys 11 the belt reaches again run parallel to each other in a horizontal plane.

As shown in Figs. 1, 2 and 4, the track-forming shield 3 is formed in sections extending along the 60 horizontal reaches of the line and terminating at the corner pulleys. These shield sections are twisted to conform to the twists of the belt reaches 1^a and 2^a and dispose the belt tracks 4 flat against the conveyer faces of the belts. 70 The central ridge 5 of each shield section extends forward from the body of the shield as at 5^a and is curved inward between the pulleys 15 and 16 so that its end lies within the peripheries of said pulleys. The adjacent ends of the two shield 75 sections may also be formed with prongs 22 to

project into the grooves 17 of the pulleys and guide a conveyed sheet from the first shield section to the pulleys and from the pulleys to the following shield section. A conveyed sheet is dragged upward along the ascending length of 80 the line which it will be understood also has a track-forming shield. Thence the sheet is conveyed smoothly without interruption along the twisted shield section of the first horizontal reach of the line, around the peripheries of the corner pulleys to the second twisted shield section and along the latter toward the discharge point. The sets of belt-twisting pulleys at the opposite sides of the corner permit the sheet to pass them freely. 85

In the shield modification shown in Figs. 7 and 90 8 the shield extends continuously around the corner pulleys and has one of its tracks canted slightly transversely to conform to the cant of the pulley 16. The belt tracks 4 are slotted around the pulleys as at 23 leaving narrow strips 95 of the track which are disposed in the grooves 17 of the pulleys. The peripheral ridges of the pulleys project through said slots to engage the belts and the conveyed sheets.

At the bend in the conveyer line there is a 100 skeleton frame structure supporting all of the pulleys at this point. This structure comprises four vertical corner members 24 in rectangular arrangement secured at their upper ends to the ceiling and having their lower ends connected 105 by horizontal members 25. For supporting the pulleys 13 there are two horizontal bracket bars 26 mounted upon the vertical frame members at opposite sides of the frame. Each bar is forked at its ends, as at 27, to straddle the frame members, and the forks have set screws 28 to detachably and adjustably lock the bars to the frame. A horizontal shaft 29 connects said bars and has its ends detachably joined thereto in any suitable manner. Mounted upon said shaft are two 115 hanger blocks 30 forked to straddle the shaft and having set screws 31 to detachably and adjustably lock them to the shaft. Said blocks have depending stub shafts 32 upon which the pulleys 13 are rotatably mounted. Spaced below the bars 120 26 are two similar bracket bars 33 similarly mounted upon the vertical frame members in spaced relation at one side of the frame, to support the pulleys 15 and 16. Said pulleys are rotatably mounted upon a bent shaft 34 having 125 a vertical lower portion for the pulley 15 and a canted upper portion for the pulley 16. Forks 35 are fixed to the ends of said shaft, and eye-bolts 36 have their eyes fitted in said forks and secured by pins. The shanks of the bolts are 130 screwed into threaded sockets on the bars 33. At the opposite side of the frame are two similar bars 37 similarly mounted. Inclined bars 38 supporting the adjacent ends of the track-forming shield sections are bolted to the bars 37. 135

The pulleys 18, 19, 20 and 21 are also supported by a skeleton frame structure through which the conveyer line passes. This structure comprises four vertical corner rods 39 secured at their upper ends to the ceiling and connected together at 140 their lower ends by bars 40. Pulleys 18 and 19 are rotatably mounted on a shaft 41 and pulley 20 is rotatably mounted on a shaft 42. Each shaft is bolted at its end to forked blocks 43 which straddle two of the vertical frame rods and are 145 detachably and adjustably secured to the rods by set screws 44. The pulley 21 is rotatably mounted upon a shaft 45 canted horizontally with reference to the first shafts and supported at its ends by eyebolts 46. The shanks of the latter ex- 150

tend through bores in forked blocks 47 and are adjustably secured by nuts. The blocks 47 straddle two of the vertical frame bars and are detachably and adjustably secured thereto by set screws 48. The set of pulleys 18^a, 19^a, 20^a and 21^a are similarly supported in a similar frame structure. Each of said frame structures also supports a cross bar 50 to which the shield is secured. All of the belt twisting pulleys are mounted for adjustment into proper cooperative relation to each other and all are preferably crowned.

What I claim is:

1. A drag belt sheet conveyer line having two continuous line reaches disposed at an angle to each other to define a corner in the line and comprising a pair of companion conveyer belts trained to run side by side along the line in transversely spaced relation; pulleys at said corner in the line and pulleys at opposite sides of the corner cooperating to twist both belts and train them around the corner in transversely spaced relation; and drag track means opposed to the conveyer faces of the belts and extending along said reaches of the line and conforming to the twist of the belts to hold a sheet to both belts for drag conveyance continuously along both reaches of the line.

2. A drag belt sheet conveyer line having two continuous line reaches disposed at an angle to each other to define a corner in the line and comprising a pair of companion conveyer belts to run side by side along the line in transversely spaced relation; a pair of pulleys mounted side by side at said corner with the axis of one canted with respect to the axis of the other; two sets of pulleys spaced along the line from opposite sides of said corner pulleys and mounted with their axes in angular relation to the axes of the corner pulleys, each set including a pair of pulleys directly on the line and a pulley spaced transversely outward from the line to form a loop in one of the belts, one of said loop-forming pulleys on the line being canted with respect to the other to cooperate with the said canted corner pulley to form a twist in the belt and train it around the corner, and a pulley cooperating with the other corner pulley to form a twist in the other belt and train it around the corner in said spaced relation to the first belt; sheet-guiding and retaining means extending along the twisted lengths of said belts and opposed to the conveyer faces thereof to hold an interposed sheet to both belts for drag conveyance with a medial portion of the sheet bridging the space between the belts; and means to flex said medial portion of the sheet outward between the belts.

3. A drag belt conveyer line having two continuous line reaches disposed at an angle to each other to define a corner in the line and comprising a pair of companion conveyer belts to run side by side along the line in transversely spaced relation; a pair of pulleys mounted side by side at said corner with the axis of one canted with respect to the axis of the other; a set of pulleys spaced along the line from said corner pulleys and mounted with their axes in angular relation to the axes of the corner pulleys, the set including a pair of pulleys directly on the line and a pulley spaced outward from the line to form a loop in one of the belts, one of said loop-forming pulleys on the line being canted with respect to the other to cooperate with said canted corner pulley to form a twist in the belt and train it around the corner, and a pulley cooperating with the other corner pulley to form a twist in the other belt

and train it around the corner in said spaced relation to the first belt; and guiding and retaining means extending along the twisted lengths of said belts and opposed to the conveyer faces thereof to hold an interposed article to both belts for drag conveyance with a medial portion of the article bridging the space between the belts.

4. A drag belt sheet conveyer line having two continuous line reaches disposed at an angle to each other to define a corner in the line and comprising a pair of companion conveyer belts to run side by side along the line in transversely spaced relation; a pair of pulleys mounted side by side at the corner with the axis of one canted with respect to the axis of the other; pulleys spaced along the line from said corner pulleys and mounted with their axes in angular relation to the axes of the corner pulleys and cooperable with the latter to twist the belts and train them around the corner in said spaced relation; sheet guiding and retaining means extending along the twisted lengths of said belts and opposed to the conveyer faces thereof to hold an interposed sheet to both belts for drag conveyance with a medial portion of the sheet bridging the space between the belts; and means to flex said medial portion of the sheet out of the plane of the belts.

5. A drag belt sheet conveyer line having two continuous line reaches disposed at an angle to each other to define a corner in the line and comprising a pair of companion conveyer belts to run side by side along the line in transversely spaced relation; a pair of pulleys mounted side by side at the corner; a set of pulleys spaced along the line from said corner pulleys and mounted with their axes in angular relation to the axes of the corner pulleys and including pulleys training one of the belts outward and back to the line in a loop and cooperating with one of said corner pulleys to form a twist in the belt and train it around the corner, and a pulley cooperating with the other corner pulley to form a twist in the other belt and train it around the corner in said spaced relation to the first belt; sheet guiding and retaining means extending along the twisted lengths of said belts and opposed to the conveyer faces thereof to hold an interposed sheet to both belts for drag conveyance with a medial portion of the sheet bridging the space between the belts; and means to flex said medial portion of the sheet out of the plane of the belts.

6. A drag belt sheet conveyer line having two continuous line reaches disposed at an angle to each other to define a corner in the line and comprising a pair of companion conveyer belts to run side by side along the line in transversely spaced relation; a pair of pulleys mounted side by side at said corner; a set of pulleys spaced along the line from said corner pulleys and mounted with their axes in angular relation to the axes of the corner pulleys the set including a pair of pulleys directly on the line and a pulley spaced transversely outward from the line to form a loop in one of the belts, one of said loop-forming pulleys on the line being canted with respect to the other to cooperate with one of said corner pulleys to form a twist in the belt and train it around the corner; and a pulley cooperating with the other corner pulley to form a twist in the other belt and train it around the corner in said spaced relation to the first belt; sheet-guiding and retaining means extending along the twisted lengths of said belts and opposed to the conveyer faces thereof to hold an interposed sheet to both belts for drag conveyance with a medial portion

of the sheet bridging the space between the belts; and means to flex said medial portion of the sheet outward between the belts.

7. A drag belt sheet conveyer line having two continuous line reaches disposed at an angle to each other to define a corner in the line and comprising a plurality of companion conveyer belts to run side by side along the line in transversely spaced relation; pulleys spaced along the line from said corner; belt-training means at said corner cooperating with said pulleys to twist the belts and train them around the corner in said spaced relation; sheet guiding and retaining means extending along the twisted lengths of the belts to hold an interposed sheet to both belts for drag conveyance; and means extending between the belts and along the twisted lengths thereof to flex the sheet outward between the belts.
8. A drag belt sheet conveyer line having two continuous line reaches disposed at an angle to each other to define a corner in the line and comprising a pair of companion conveyer belts trained to run side by side along the line in transversely spaced relation; pulleys at said corner in the line and pulleys at opposite sides of the corner and canted with respect to said corner pulleys and cooperating therewith to twist both belts and train them around the corner in transversely spaced relation; and drag tracks opposed to the conveyer faces of the belts and extending along said reaches of the line and conforming to the twist of the belts to hold a sheet to both belts for drag conveyance continuously along both reaches of the line.

9. A drag belt sheet conveyer line having two continuous line reaches disposed at an angle to each other to define a corner in the line and comprising a plurality of pulleys mounted side by side in said corner with their axes canted relatively to each other; means forming a plurality of side by side drag tracks extending along the line and around the corner over the peripheries of said pulleys and relatively canted at the corner to conform to the cant of the pulleys; a plurality of conveyer belts to run side by side in transversely spaced relation along said tracks with a medial portion of the sheet bridging the space between the belts; and a rib between said tracks and extending around the corner to flex said medial portion of the sheet between the belts, the tracks having slots extending around the corner and the pulleys having peripheral portions protruding through said slots to engage the belts.

10. A drag belt sheet conveyer line having two continuous line reaches disposed at an angle to each other to define a corner in the line and comprising a plurality of pulleys mounted side by side in said corner; means forming a plurality of side by side drag tracks extending along the line and around the corner over the peripheries of said pulleys; a plurality of conveyer belts to run side by side in transversely spaced relation along said tracks with a medial portion of the sheet bridging the space between the belts; and a rib between said tracks and extending around the corner to flex said medial portion of the sheet between the belts, the tracks having cut-outs at the corner and the pulleys having peripheral portions protruding through said cut-outs to engage the belts.

11. A drag belt sheet conveyer line comprising a plurality of companion conveyer belts trained to run side by side in the same direction in transversely spaced relation; a set of pulleys to train

one of said belts including a pair of pulleys mounted directly on the line and a pulley mounted in a position spaced transversely outward from the line, said pulleys training the belt in a loop at an intermediate point in the line and one of said pulleys on the line being in a canted position with respect to the other, for the purpose set forth; sheet guiding and retaining means extending along the line and opposed to the conveyer faces of the belts to hold an interposed sheet to both belts for drag conveyance along the line with a medial portion of the sheet bridging the space between the belts; and means to flex said medial portion of the sheet.

12. A drag belt conveyer line comprising a conveyer belt extending along the line; a set of pulleys training said belt and including a pair of pulleys mounted directly on the line and a pulley mounted in a position spaced transversely outward from the line and cooperating with said pair of pulleys to form a loop in the belt at an intermediate point in the line, one pulley of said pair being canted with respect to the other, for the purpose set forth; and means forming a drag track extending along the line and opposed to the conveyer face of the belt.

13. A belt conveyer line having two continuous line reaches disposed at an angle to each other to define a corner in the line and comprising a pair of companion cooperative conveyer belts to run side by side along the line in transversely spaced relation; a pair of pulleys mounted side by side at said corner, with the axis of one canted with respect to the axis of the other; two sets of pulleys spaced along the line from opposite sides of said corner pulleys and mounted with their axes in angular relation to the axes of the corner pulleys, each set including a pair of pulleys directly on the line and a pulley spaced transversely outward from the line to form a loop in one of the belts, one of said loop-forming pulleys on the line being canted with respect to the other to cooperate with the said canted corner pulley to form a twist in the belt and train it around the corner, and a pulley cooperating with the other corner pulley to form a twist in the other belt and train it around the corner in said spaced relation to the first belt; and means extending along said belts and opposed thereto to hold an article to both belts for continuous conveyance along the line reaches in succession.

14. A belt conveyer line having two continuous line reaches disposed at an angle to each other to define a corner in the line and comprising a pair of companion cooperating conveyer belts to run side by side along the line in transversely spaced relation and convey an article by engagement of both belts therewith; a pair of pulleys mounted side by side at said corner with the axis of one canted with respect to the axis of the other; and two sets of pulleys spaced along the line from opposite sides of said corner pulleys and mounted with their axes in angular relation to the axes of the corner pulleys, each set including a pair of pulleys directly on the line and a pulley spaced transversely outward from the line to form a loop in one of the belts, one of said loop-forming pulleys on the line being canted with respect to the other to cooperate with the said canted corner pulley to form a twist in the belt and train it around the corner, and a pulley cooperating with the other corner pulley to form a twist in the other belt and train it around the corner in said spaced relation to the first belt.

15. A belt conveyer line having two continu-

- ous line reaches disposed at an angle to each other to define a corner in the line and comprising a pair of companion conveyer belts to run side by side along the line in transversely spaced relation; a pair of pulleys mounted side by side at the corner; a set of pulleys spaced along the line from said corner pulleys and mounted with their axes in angular relation to the axes of the corner pulleys and including pulleys training one of the belts outward and back to the line in a loop and cooperating with one of said corner pulleys to form a twist in the belt and train it around the corner, and a pulley cooperating with the other corner pulley to form a twist in the other belt and train it around the corner in said spaced relation to the first belt; and means extending along the twisted lengths of said belts and opposed to the conveyer faces thereof to hold an article to both belts for conveyance. 10
16. A conveyer line having two continuous line reaches disposed at an angle to each other to define a corner in the line and comprising a plurality of companion conveyer belts running side by side along both of said line reaches in transversely spaced relation; cooperating belt training means at said corner and at opposite sides of the corner training said companion belts to run in substantially the same plane along both line reaches and twisting the belts out of said plane 25 to train them around the corner in transversely spaced relation; and means opposed to said belts and extending therealong to hold an article to both belts for conveyance continuously along both reaches of the line. 30
17. A drag belt conveyer line having two continuous line reaches disposed at an angle to each other to define a corner in the line and comprising a plurality of companion drag conveyer belts running side by side along both of said line reaches in transversely spaced relation; cooperating belt training means at said corner and at opposite sides of the corner training said companion belts to run in substantially the same plane along both line reaches and twisting the belts 40 out of said plane to train them around the corner; and drag track means opposed to said belts and extending therealong to hold an article to both belts for drag conveyance continuously along both reaches of the line. 45
18. A conveyer line having two continuous line reaches disposed at an angle to each other to define a corner in the line and comprising a plurality of substantially flat companion cooperating conveyer belts trained to run side by side along said line reaches in transversely spaced relation and in substantially the same plane to convey an article by engagement of both belts therewith; belt training means at said corner in the line; and belt training means on said reaches of the line at 50 opposite sides of the corner and cooperative with said training means at the corner to twist the companion belts and train them to run around the corner in said transversely spaced side by side conveying relation without flexure of the belts in the plane thereof. 55
19. A conveyer line having two continuous line reaches disposed at an angle to each other to define a corner in the line and comprising a plurality of substantially flat companion cooperating conveyer belts trained to run side by side along said line reaches in transversely spaced relation and in substantially the same plane to convey an article by engagement of both belts therewith; belt training means at said corner in the line; and belt training 60 means on said reaches of the line at opposite sides of the corner and cooperative with said training means at the corner to twist the companion belts and train them to run around the corner in said transversely spaced side by side conveying relation without flexure of the belts in the plane thereof. 65
20. A conveyer line having two continuous line reaches disposed at an angle to each other to define a corner in the line and comprising a plurality of substantially flat companion cooperating conveyer belts trained to run side by side along said line reaches in transversely spaced relation and in substantially the same plane; belt training means at said corner in the line, and belt training means on said reaches of the line at opposite sides of the corner and cooperative with said training means at the corner to twist the companion belts and train them to run around the corner in said transversely spaced side by side conveying relation without lateral flexure of the belts in the plane thereof, said belt training means at the corner and on the line reaches comprising pulleys, and the belt training means on the line reaches including pulleys mounted with their axes canted with relation to the corner pulley 70
21. A drag conveyer line having two continuous line reaches disposed at an angle to each other to define a corner in the line and comprising a plurality of substantially flat companion conveyer belts trained to run side by side along said line reaches in transversely spaced relation and in substantially the same plane; belt training means at said corner in the line; belt training means on said reaches of the line at opposite sides of the corner and cooperative with said training means at the corner to twist the companion belts and train them to run around the corner in said transversely spaced side by side conveying relation without lateral flexure of the belts in the plane thereof; and means extending along said belts and opposed thereto to hold an article to both belts for continuous drag conveyance along one reach of the line, around the corner and along the other reach of the line. 80
22. A drag belt sheet conveyer line having two continuous line reaches disposed at an angle to each other to define a corner in the line and comprising a plurality of substantially flat companion conveyer belts trained to run side by side along said line reaches in transversely spaced relation and in substantially the same plane; belt training means at said corner in the line; and belt training means on said reaches of the line at opposite sides of the corner and cooperative with said training means at the corner to twist the companion belts and train them to run around the corner in said transversely spaced side by side conveying relation without lateral flexure of the belts in the plane thereof; drag track means extending along said belts and opposed thereto to hold a sheet to the belts for continuous conveyance along one reach of the line, around the corner and along the other reach of the line with the medial portion of the sheet bridging the space between the belts; and sheet flexing means extending along the line to flex said medial portion of the sheet out of the plane of the belts. 120
23. A belt conveyer line having two line reaches disposed in substantially the same plane and at an angle to each other to define a corner in the line 130

line and comprising a pair of substantially flat companion cooperating conveyer belts trained to run side by side along both of said line reaches and substantially in said plane; belt training means including pulleys mounted with their axes in canted relation to each other to twist said companion belts and train them around said corner of the line in side by side cooperating conveying relation without flexure of the belts 5 in the plane thereof; and means extending along said belts and opposed thereto to hold an article to both belts for continuous conveyance along the line reaches in succession.

24. A belt conveyer line having two line reaches 10 disposed in substantially the same plane and at an angle to each other to define a corner in the line and comprising a plurality of substantially flat companion cooperating conveyer belts trained to run side by side along both of said line reaches 20 and substantially in said plane; and belt training means including pulleys mounted with their axes in canted relation to each other to twist said companion belts and train them around said corner of the line in side by side cooperating conveying 25 relation without flexure of the belts in the plane thereof.

25. A belt conveyer line having two line reaches disposed in substantially the same plane and at an angle to each other to define a corner in the 30 line and comprising a plurality of substantially flat companion cooperating conveyer belts trained to run side by side along both of said line reaches and substantially in said plane; belt training means including pulleys mounted with their axes 35 in canted relation to each other to twist said companion belts and train them around said corner of the line in side by side cooperating conveying relation without flexure of the belts in the plane thereof; and means to relatively adjust said 40 pulleys into accurate cooperating belt training relation.

26. A conveyer line comprising a pair of companion conveyer belts trained to run side by side along the line; a set of pulleys to train one of said belts including a pair of pulleys mounted directly on the line and a pulley mounted in a position spaced transversely outward from the line, said pulleys training the belt in a loop at an intermediate point in the line and one of said pulleys on the line being canted with respect to the other for the purpose set forth; and means opposed to the belts and extending therealong to hold an article to both belts for conveyance. 80 85

27. A conveyer line comprising a conveyer belt extending along the line; a set of pulleys training said belt and including a pair of pulleys mounted directly on the line and a pulley mounted in a position spaced transversely outward from the line and cooperating with said pair of pulleys to form a loop in the belt at an intermediate point in the line, one pulley of said pair being canted with respect to the other, for the purpose set forth; and means opposed to the belt and extending therealong to hold articles thereto for conveyance. 90 95

28. A conveyer line comprising a substantially 100 flat conveyer belt extending along the line; a set of pulleys training said belt and including a pair of pulleys mounted directly on the line and a pulley mounted in a position spaced transversely outward from the line and cooperating with said 105 pair of pulleys to form a loop in the belt at an intermediate point in the line, one pulley of said pair being canted with respect to the other, for the purpose set forth and the other pulley of the pair and said outwardly spaced pulley having 110 their axes parallel; and means opposed to the belt and extending therealong to hold articles thereto for conveyance. 115
